UNITED STATES PATENT OFFICE

SIDNEY J. FINN, OF BEVERLY, MASSACHUSETTS, ASSIGNOR TO UNITED SHOE MACHINE CORPORATION, OF PATERSON, NEW JERSEY, A CORPORATION OF NEW JERSEY

MACHINE FOR AND METHOD OF HEEL-SEAT FITTING

Application filed July 15, 1926. Serial No. 122,727.

This invention relates to the manufacture of shoes and is herein set forth by way of illustration with particular reference to its use in the removal of surplus material from the peripheries of the heel-seats of the soles of shoes to prepare them for the attachment of wood heels, though in some of its aspects the invention is not limited to such use.

In the manufacture of shoes to which wood and some other kinds of heels are to be attached, the heel-seat surface of the sole of each shoe is fitted for the attachment of a heel by removing surplus material from its periphery to form a convex surface substantially complementary to the concave attaching surface of the heel so that a firm attachment of the heel may be secured and the upper edge of the heel may be brought into close engagement with the shoe upper.

20 This heel-seat fitting operation was long performed by hand, but of recent years has been done increasingly by machines.

One object of the present invention is to provide an improved heel-seat fitting machine of simple and rugged construction by means of which a good quality of work may be done at high speed without requiring excessive skill on the part of the operative.

A feature of the invention, considered in its machine aspect, resides in a novel machine organization for trimming a piece of work, such as a piece of shoe stock, to form a convex surface thereon. As disclosed herein the invention is embodied in a heel-seat fitting machine provided with a cutter having a cutting edge curved about an axis extending, during the trimming of the sides of the heel-seat portion of the sole of a shoe, in the general direction of the length of the shoe. As illustrated, this cutter is formed as a hollow cylinder with a circular cutting edge at an open end thereof and rotates about a horizontal axis. Cooperating with this cutter is a movable work support, together with suitable mechanism arranged to cause relative movement of the cutter and the work support so that the heel end of a shoe may be presented to the cutting edge at the open end of the cutter and moved inside the cylinder to cause the cutter to trim

surplus material from the horseshoe-shaped area about the periphery of the heel-seat of the sole of the shoe. With such an organization the cutter may be made effective first to trim the rear end of the heel-seat and then progressively to remove surplus material simultaneously from both sides of the heel-seat forwardly to a point adjacent to the heel-breast line.

In heel-seat fitting it is common to distort the peripheral portion of the heel-seat of the sole so as to position it away from the upper during the trimming operation, thereby protecting the upper and allowing the trimming cut to produce a bevel the outer edge of which is a substantial distance from the edge of the heel-seat of the sole. Following this practice, and in accordance with other features of the invention, novel means are provided to distort the sole, said means being arranged to engage the rand crease at the rear of the shoe, distorting the rear end of the heel-seat of the sole away from the shoe upper. The distorting means then follows around the heel-seat, acting progressively at opposed points to lift the edge of the sole somewhat away from the upper prior to the action of the cutter as the shoe and cutter are given a relative movement of trans-

lation.

It is a further object of the invention to provide a heel-seat fitting machine organization including an improved work support constructed and arranged to facilitate the presentation of a shoe to a trimming cutter, for example to a cylindrical cutter such as is described above. I have found that the proper presentation of a shoe to a hollow, cylindrical cutter, in such a manner as to cause said cutter to bevel first the rear end of the sole and then the sides of the heel-seat of the sole, preferably involves relative movement between the cutter and the shoe successively in a plurality of different directions, the shoe being presented first in a downwardly tilted position with respect to the cutter so that said cutter may act upon the rear end of the heel-seat, and then in a substantially horizontal position as the cutter acts upon the side edges of the heel-seat.

Accordingly, another feature of the invention resides in a heel-seat fitting machine organization including novel shoe-supporting and presenting mechanism by means of which the shoe is given both a tilting movement and a movement of translation automatically to present the shoe to the cutter for the heel-seat fitting operation. As illustrated, this mechanism embodies a pivotally supported runway in which there is mounted a slidable carrier upon which the shoe support itself is pivotally mounted, said carrier being arranged for movement along the runway in a path toward and away from the trimming cutter to cause the heel end of the shoe to be projected into the hollow, cylindrical cutter as the latter operates upon the heel-seat of the shoe.

When shoes are to be fitted for Cuban heels, for example, the bevel cuts along the sides of the heel-seat are terminated in transverse shoulders against which the breast of the heel may be abutted. A further feature of the invention resides in a cutter mounted for pivotal movement about the axis of the trimming cutter so that it may be moved transversely of the sole to cut upright shoulders therein adjacent to the heel-breast line. Such a cutter may preferably be operator-controlled.

When shoes are to be fitted for other types of heels, such as Louis heels for example, the bevel cuts along the sides of the heel-seat may be brought out to the tread surface of the sole without forming any abrupt shoulder. Moreover, it frequently is desired to make a transverse cut adjacent to the heel-breast line extending forwardly and downwardly into the sole of the shoe to form a stiff tongue or flap beneath which the overhanging breast of a Louis heel may be placed. To these ends still other features of the invention reside in an organization whereby the machine may be caused to operate in such a fashion that it will fit the heel-seat in accordance with either or both of these methods. Accordingly, the illustrated machine is arranged so that the shoe may be tilted in various ways as it is moved in a generally horizontal direction to present the heel end of the shoe within the cutter, thereby to cause the cutter to produce the desired effect upon the sole.

In another of its aspects the invention comprises a novel method of trimming surplus material from a work piece to produce a convexly curved surface thereon, said method being characterized by the introduction of the work piece into the interior of a hollow, substantially cylindrical, rotating knife, and causing mutual engagement of and relative movement between the work piece and the edge of the knife, thereby causing the knife to form a convexly curved surface upon the work piece.

In still another aspect the invention consists in the provision of an improved method of heel-seat fitting according to which the rear end of a shoe is introduced into the interior of a hollow, substantially cylindrical, rotating knife and relative movement of the shoe and knife in the general direction of the axis of rotation of the knife is produced to bring the sole and the cutting edge of the knife into mutual engagement. This relative movement may be continued along a plurality of angularly related directions to cause material to be removed first from the rear end of the heel-seat and then from a side or simultaneously from opposite sides of the heel-seat.

These and other features of the invention will now be described with reference to the accompanying drawings, in which:

Fig. 1 is a side elevation, partly in section, of a heel-seat fitting machine embodying the present invention;

Fig. 2 is a front elevation with parts in section;

Fig. 3 is a plan view of the slidable shoe supports in their runway;

Fig. 4 is a fragmentary perspective view of the heel end of a shoe, showing a horse-shoe-shaped piece of surplus material which has been partially removed by the trimming cutter;

Fig. 5 is a similar view showing the completed heel-seat after the transverse cutter has been actuated to complete the removal of surplus material and to form suitable shoulders as for a Cuban heel;

Fig. 6 is a transverse, vertical section through the runway and support slides, showing operator controlled mechanism for tilting the runway;

Fig. 7 is a vertical section on the line VII—VII of Fig. 1;

Fig. 8 is a fragmentary plan view showing a portion of the trimming cutter and one of the rand crease engaging fingers;

Fig. 9 is a side elevation of the same parts;

Fig. 10 is a prespective view of the heel of a shoe fitted for a Louis heel, while

Fig. 11 shows the same shoe with the additional cut necessary to provide a stiff tongue beneath which the breast of a Louis heel may be inserted;

Figs. 12, 14, 16 and 18 are diagrammatic views illustrating the relative position of an actuating slide and the slidable shoe support with relation to one another and to the runway during successive steps of the operation of presenting the shoe to the cutter;

Figs. 13, 15, 17 and 19 show the corresponding positions of the shoe, the cutter and associated parts during the same steps;

Fig. 20 is a similar diagram illustrating the position assumed by the parts when the

runway is tilted and the cutter has completed the bevel cut illustrated in Fig. 10 and has emerged from the sole;

Fig. 21 shows the relative position of the shoe and cutter at the completion of this step;

Fig. 22 is a similar diagram illustrating the position assumed by the parts when the machine is used to form the "double flap", and

Fig. 23 shows the position of the cutter, the shoe, and its carrier at the completion of this operation.

The trimming away of surplus material is effected, in the use of the illustrated machine, by means of a hollow skiving cutter 20 of the "ring knife" type which is mounted for rotation about a horizontal axis as best shown in Fig. 1. This rotary skiving cutter 20 is formed with a hollow cylindrical blade having at one end a sharpened circular cutting edge 22 and is provided with a transverse flange 24 by means of which it is attached to and supported upon a sleeve 26 mounted for rotation in uprights 28 and 30 formed upon a base member 32. Power applied from any suitable source to a driving pulley 34 causes continuous rotation of the cutter during the operation of the machine. It will be noted that the cylindrical cutter 20 is of such a size that the heel end of a shoe may readily be inserted bodily within the cutter. The cutter is caused to skive and bevel the side edges of the sole adjacent to the heel-seat and to this end its diameter is such that it will cut the desired bevel simultaneously upon opposite sides of the sole forming a convexly curved surface, as indicated in Fig. 7 where the dotted circle indicates the position of the edge 22 of the cutter.

In order that these bevel cuts may be so formed upon the sole that they will be disposed a substantial distance inwardly from the periphery of the heel-seat of the shoe, relatively narrow rand crease engaging fingers 40 and 42 (Figs. 7, 8 and 9) are provided which have sharpened ends beveled in two directions, as indicated in Figs. 7 and 9, and tapered lengthwise at 44, as shown in Fig. 8, so that they may be presented in the rand crease of the shoe adjacent to the extreme rear end thereof and will be pushed apart during the movement of the shoe into engagement with the cutter and will continue to follow along the rand crease at the sides of the heel-seat. To this end the fingers 40 and 42 are mounted in the arms 46 and 48 extending laterally and forwardly from supporting plates 50 and 52 (Figs. 1 and 7), which are pivotally mounted upon the sleeve 26 of the cutter and are guided between retaining plates 54 and 56 separated by spacing members 58 and secured in turn to a sleeve 60 surrounding the sleeve

26 within the upright 30. These supporting plates are individually connected by means of links 62, 63, to a slide 64 which is disposed below said plates and which is mounted upon a stud 66 in the base 32 and is provided with a spring 68 urging said slide downwardly to press the rand crease engaging fingers resiliently into the creases of the shoe. The fingers 40 and 42 are pivoted in hollow transverse extensions 47 and 49 extending inwardly from the arms 46 and 48. In order that the fingers may be self-adjusting and normally retained in a horizontal plane, flat springs 70 are provided (Figs. 8 and 9) attached to the extensions 47 and 49 and bearing upon flats formed upon the outer ends of the fingers themselves. Pins 72 in the extensions 47 and 49 engaging grooves in the fingers 40 and 42 aided by shoulders 74 (Fig. 8) upon the fingers prevent inward or outward movement through the bearings in the extensions 47 and 49 as the fingers are operated, progressively to distort the periphery of the sole.

The action of the fingers 40 and 42 in distorting the edges of the sole is assisted by a hold-down illustrated as a pressure roll 80 supported just ahead of the cutting edge 22 in the adjustable outer part 82 of an arm 84 which is pivoted upon a pin 86 extending between brackets 88 formed upon the upright 30. A spring 90 (Fig. 1) urges the roll into contact with the sole of the shoe to hold the sole firmly against the last for the action of cutter 20. The downward movement of roll 80 is limited by means of a stop screw 92 adjustable in arm 84 and bearing against a fixed portion of the machine forward of the pivot pin 86. Adjustment of the length of arm 84 is provided for by a clamp bolt 94 passing through a slot in the parts 82 and 84.

The presentation of a shoe to the action of the cutters is greatly facilitated in the present construction by the construction and arrangement of the work support, the parts of which are best illustrated in Figs. 1, 2, 3 and 6. This support comprises a runway 100, pivotally mounted at one end on a transverse pin 102 upon the base 32. This runway is grooved (Figs. 2 and 6) for the reception of a bifurcated slide or carrier comprising separated plates 104 and 106, which are joined at 109 (see Fig. 3) for simultaneous movement and are provided with rearwardly sloping uprights 108 and 110 between which there is carried a shoe support 112 (Figs. 1 and 2). This support 112 is provided with lateral hangers 114 by means of which it is pivotally mounted between the uprights 108 and 110. Plates 105 and 107 (Figs. 2 and 6) retain the bifurcated slide in the groove of the runway 100. The shoe support 112 is provided at its rear end with a last pin 116, upon which the last

118 of a shoe 120, the sole 122 of which is to be fitted, may be mounted, and the toe of said shoe is supported by means of a toe support 124 vertically adjustable by means of its threaded shank 126 in the forward end of the shoe support 112. This toe support 124 is U-shaped, as shown in Fig. 2, and is provided with a saddle formed by a transverse leather strap 128 secured at its ends by means of clamping bolts 130. The tilting of the shoe upon the carrier is effected by means of a bell-crank lever 132 having a bifurcated upper end 134 which is slotted for engagement with a transverse pivot pin 136. This bell-crank lever 132 is pivotally supported at 138 between two uprights 140 and 142, which are also carried upon the side plates 104 and 106, respectively, of the slideable support or carrier in the runway 100. The lower forked end 144 of the bell-crank lever 132 engages a transverse pin carried by lugs 145 (Fig. 1) extending upwardly from the top of an actuating slide 150 (Figs. 1, 2 and 4). This actuating slide 150 is provided with teeth 151 upon its lower surface for engagement with a pinion 152 carried upon a transverse shaft 154 in the runway 100 and extending laterally therefrom for engagement with and operation by a detachable crank 156. By means of this crank, movement of the actuating slide 150 lengthwise of the runway 100 may be imparted, and this movement, by suitable controlling mechanism to be described, causes a tilting movement of the shoe support 112 through the bell-crank lever 132 and a movement of translation of the shoe support through the divided slide 104 and 106. In order that the turning of the crank 156 may move the parts so as to cause the desired sequence of operations, spring-pressed latches 160 and 162 are mounted inside the slide member 104, as shown in Figs. 2 and 3, and the actuating slide 150 is provided with notches 164 and 166 for engagement by said latches, respectively. The latches in the slide 104 are spring-pressed to cause engagement of their inner ends with the slide 150 while their outer ends contact with the inner surface of the runway which is grooved, as indicated at 168, to allow said latches to be pressed outwardly to release the latches from the notches 164, 166 when the slide 104 is in such a position with respect to the runway 100 that the latches are opposite said groove. Movement of the slide 104 in the runway is limited by a stop pin 169 which may occupy either of two holes in the runway 100 (Figs. 1 and 3). At the beginning of the operation of the machine, when it is desired to mount a shoe upon the shoe support, the slides are moved to their forward positions, as indicated in Fig. 12, so that the actuating slide 150 is locked to the slide 104, and consequently to the slide 106 because slides 104 and 106 are permanently connected at 109, by means of the forward latch 160 which has engaged the notch 164 in the slide 150 and is held therein by contact with the side of the runway 100. In this position the shoe support will be tilted, as indicated in Fig. 13, because of the relative positions of the slides and their consequent effect upon the bell-crank lever 132. Here it will be easy to mount the lasted shoe upon the shoe support 112, after which the crank 156 may be operated to move the actuating slide and with it the slides carrying the shoe support 112 to bring the rotating cutter 20 into engagement with the rear end of the sole in the rand crease between the sole and the upper, this action being facilitated by the prior engagement with the shoe of the cooperating rand crease engaging fingers 40 and 42, in the position illustrated in Fig. 8, where their wedge-shaped portions, as shown in Fig. 9, tend to tilt up the rear end of the sole and facilitate the entrance of the edge 22 of the trimming cutter into the rand crease to remove surplus material from and reduce the end of the heel-seat. At this time the slides will have advanced to the position illustrated in Fig. 14, and the shoe will be in engagement with the cutter as shown in Fig. 15. It will be noted that in this position the actuating slide 150 is about to be released from the slideable support 104 because the forward latch 160 has come to a position opposite the forward end of groove 168. Continued movement of the crank 156 will therefore impart a movement to the actuating slide which will not be communicated to the slideable support 104 because the latter is held by the positive engagement of the latches 160, 162 with the ends of the groove 168 but this movement will cause tilting of the shoe about an axis at an angle to the axis of rotation of the knife through the operation of the bell-crank lever 132 to bring it to the position illustrated in Fig. 17, where it will be seen that the heel-seat portion 170 of the shoe is substantially in a horizontal plane, the cutter having entered the sole sufficiently to cut through the sole to form the bevel 172 (Figs. 5 and 11) at the rear end of the heel-seat. At this time the notch 166 in the actuating slide 150 has been brought to a position opposite to the rear latch 162 which has remained at the rear extremity of the groove 168 and is ready to be spring pressed into the notch 166. This again locks together the actuating slide 150 and the slideable support 104 for the shoe support 112 so that the shoe support may be given a movement of translation toward the trimming cutter 20 to cause the latter to cut along the sides of the heel-seat to form the beveled portions 174 simultaneously at opposite sides of the

heel-seat, creating a horseshoe-shaped flap 176 (Fig. 4) of surplus material. The movement last mentioned, considering any single point in the heel-seat, will be along 5 a rectilinear path or direction angularly related to the direction of the first movement when the rear end was beveled, these directions being for convenience considered as lying in a plane normal to the tread of 10 the sole. This will advance the parts to the position indicated in Fig. 18, with the heel end of the shoe inside the hollow cutter 20. In this position the slides 104 and 150 are locked together. At this stage the trimming 15 cutter 20 has advanced over the heel-seat and, by reason of its cylindrical form, it has simultaneously cut away the surplus material at the opposite sides of the heel-seat as the edges of the sole were progressively distorted and lifted up away from 20 the upper by the action of the rand crease engaging fingers 40 and 42. The latter, by reason of their tapered edges 44 and sharpened ends, as shown in Fig. 7, have moved 25 along in the rand crease as the shoe has been moved into the machine and have passed around the curved portions at the rear end of the heel-seat to lift up all portions of the edge of the sole the better to 30 protect the upper and to bring said edge portions of the sole into proper position for the action of the trimming cutter. In this operation they are assisted by the pressure roll 80, which bears against the sole of the 35 shoe slightly in advance of said fingers.

This part of the operation completed, it is necessary to finish the removal of the horseshoe-shaped portion 176 and to make cuts adjacent to the heel breast line in accordance with the type of heel to be applied 40 to the shoe. If a heel of the Cuban type is to be used, then commonly the surplus material 176 will be removed by transverse cuts adjacent to the heel-breast line forming 45 shoulders 178 (Fig. 5) against which the breast of the heel may be abutted. For this operation the machine is provided with an auxiliary cutter or knife blade 180 mounted at the outer end of an arm 182 just forward 50 of the cutting edge 22 of the trimming cutter 20, and provision is made for swinging said arm to carry the knife 180 across the sole to make the transverse cuts forming shoulders 178. To this end the arm 55 182 is formed as an extension from a disk-shaped plate 184 mounted to rotate (see Fig. 1) upon an enlarged portion 61 of the sleeve 60 and having a flange 186 surrounding the outer edge of the retaining plate 54 which is secured to said enlarged portion 61 by suitable screws. Movement of the plate 60 184 and the knife 180 carried thereby may be imparted by means of an operator controlled device in the form of a treadle rod 65 188 connected to the flange 186. The plate

184 is biased to its initial position by means of a spring 190.

If, on the other hand, a Louis heel or a heel of that type is to be applied to the shoe, it may be preferred so to operate the machine that beveled cuts 192 and 194 (Fig. 10) may be formed at the sides of the heel-seat 170 adjacent to the heel-breast line. With this style of heel the thin overhanging breast of the heel overlies the sole of the shoe from which there has been skived a covering flap 196 which, after the application of the heel, is cemented to its breast surface. With the same type of heel it sometimes is desired to make an additional cut forwardly and downwardly into the sole of the shoe adjacent to the heel-breast line to form an additional stiff flap or tongue 198, which is the "double flap" of United States Letters Patent No. 1,527,963, granted February 24, 1925, upon the application of Preo and Henne.

To facilitate these latter operations for Louis heels, the machine is provided with mechanism for tilting the runway 100 in order to change the path of movement of the shoe so that by giving the shoe support an additional movement of translation with the runway 100 tilted downwardly the trimming cutter 20 may be caused to emerge from the sole in the position illustrated in Fig. 21 to form the beveled cuts 192 and 194. For this purpose the runway is supported at its under side upon a cam 202 (Figs. 1, 21 and 23) carried upon a transverse shaft 204 passing through bearings 206 formed in the base 32 of the machine and attached at one end to an operator controlled tilting member 208 which is grooved at 210 for the reception of an adjustable connecting block 212 having a hand screw 214 by means of which said connecting block 212 may be positioned at any desired point in the length of the groove 210 and especially at one end or the other thereof. The treadle rod 216 is attached to the connecting block 212 and is normally held in upper position by means of a spring 218. In this position, as it is held by the spring 218, the cam 202 is so disposed with respect to the runway 100 that said runway is held substantially parallel to the base 32 of the machine. If now the connecting member 212 is clamped by means of the hand wheel 214 at the forward end of the groove 210, a depression of the treadle rod 216 will be effective to lower the forward end of the runway 100, as indicated in Fig. 21. Movement of the tilting member 208 in this direction is limited by means of an adjustable stop screw 220 carried by a bridge 222 secured to the outer side of the base 32. It will be recalled that the movement of the slideable support in the runway 100 toward the rear of the machine is limited by a stop pin 169. When the machine

70

100

105

110

115

120

125

130

is to be operated, as shown in Fig. 21, however, to cause the cutter to make the bevels 192 and 194, this pin is withdrawn and placed in its rearmost position as in Fig. 1, so that an additional movement of translation may be imparted to the slides by means of the actuating crank 156 to bring them to the position shown in Fig. 20.

If, in addition, it is desired to form the double flap 198 of Fig. 11, then the hand wheel 214 must be loosened and the connecting member 212 moved to the other end of the groove 210, after which a combined depression of the treadle rod 216 and the actuation of the crank 156 will be effective to move the parts into the position illustrated in Fig. 22 and to tilt the runway to a position limited by the engagement of stop screw 224 upon the bridge 222 with the other end of the actuating member 208 as shown in Fig. 23. Obviously, it will be necessary, between the two operations indicated in the diagrams of Figs. 21 and 23, to bring the shoe support forward by means of a reverse actuation of the crank 156 in order that the trimming cutter 20 may re-enter the sole at a point to the rear of the heel-breast line in order to form the double flap 198.

Having described my invention, what I claim as new and desire to secure by Letters Patent of the United States is:

1. A heel-seat fitting machine having, in combination, a work support arranged to support a shoe to be operated upon, a cutter having a cutting edge curved about an axis extending in the general direction of the length of a shoe upon said support, and means for causing relative movement of the cutter and the shoe upon the support to cause the cutter to trim surplus material from the peripheral portion of the heel-seat of a shoe.

2. A heel-seat fitting machine having, in combination, a work support arranged to support a shoe to be operated upon, means for cutting a sole transversely of its edge to form heel breast receiving shoulders therein, a cutter having a cutting edge curved about an axis extending in the general direction of the length of the shoe, and means for causing relative movement of the work support and the cutter to cause the cutter to trim surplus material from the peripheral portion of the heel-seat of a shoe upon the support.

3. A heel-seat fitting machine having, in combination, a work support arranged to support a shoe to be operated upon, a cutter having a blade curved about an axis extending in the general direction of the length of a shoe upon said support and a correspondingly curved cutting edge, and means for causing relative movement of the cutter and the shoe upon the support to cause the cutter

to trim surplus material from the periphery of the heel-seat of the shoe.

4. A heel-seat fitting machine having, in combination, a work support arranged to support a shoe sole upwardly, means for cutting a sole transversely of its edge to form heel breast receiving shoulders therein comprising a cutter having a cutting edge curved about a center located below the sole of a shoe upon the support, and means for causing relative movement of the work support and the cutter to cause the cutter to trim surplus material from the peripheral portion of the heel-seat of the shoe.

5. A heel-seat fitting machine having means for distorting the rear portion of the heel-seat of the sole of a shoe away from the shoe upper, a knife having a blade curved about an axis extending in the general direction of the length of the shoe and terminating in a correspondingly curved cutting edge, and means for causing relative movement of the shoe and the knife to cause the latter to trim surplus material from the periphery of the heel-seat of the sole of a shoe.

6. A heel-seat fitting machine having a work support arranged to support a shoe to be operated upon, means for distorting the rear portion of the heel-seat of the sole of a shoe away from the shoe upper, a knife having a cylindrical blade curved about an axis extending in the general direction of the length of the shoe and terminating in a circular cutting edge, and means for causing relative movement of the shoe and the knife to cause the latter to trim surplus material from the periphery of the heel-seat of the sole of the shoe.

7. In a heel-seat fitting machine, a hollow cutter having a cutting edge at one end thereof, and means for rotating said cutter about its axis, said cutter being constructed and arranged to receive the heel end of a shoe within the cutter to cause the cutter to remove surplus material from and to bevel the entire periphery of the heel-seat of the sole of the shoe.

8. In a heel-seat fitting machine, a hollow cylindrical cutter of such a size as to receive the heel portion of a shoe within the cutter, said cutter having a sharpened edge around an end periphery thereof a part of which is exposed for the application of work thereto, a shoe support, and means for causing relative movement of said cutter and said shoe support to introduce the heel portion of the shoe within the cutter thereby causing the cutter to remove surplus material from the heel-seat surface of the sole of a shoe on said support.

9. In a heel-seat fitting machine, a hollow cylindrical cutter having a sharpened edge around an end periphery thereof a part of which is exposed for the application of work

70

75

80

85

130

- thereto, a shoe support, and means to move said shoe support arranged to bring the heel portion of the shoe within the cylindrical cutter thereby bringing the periphery of the heel-seat of the sole of a shoe on said support into engagement with the edge of the cutter to cause the latter to remove a horseshoe shaped piece of surplus material from said heel-seat.
10. In a heel-seat fitting machine for boots and shoes, a rotary cutter rotating about an axis extending lengthwise of the shoe, said cutter constructed and arranged simultaneously to bevel the opposite sides of the heel-seat of the sole of a shoe presented thereto.
11. In a heel-seat fitting machine, a cutter, means for continuously rotating said cutter, a shoe support, and means for causing relative movement of translation of the rotating cutter and shoe support arranged to cause the cutter to trim simultaneously the opposite edges of the heel-seat of the sole of a shoe carried by said shoe support.
12. In a heel-seat fitting machine, a ring shaped cylindrical cutter, a shoe support, and means for causing relative movement of translation of the cutter and shoe support to cause the heel portion of a shoe on the support to enter the cylindrical cutter to cause the cutter to trim the opposite edges of the heel-seat of the sole of the shoe carried by said shoe support.
13. In a heel-seat fitting machine, a rotary cutter, means for rotating said cutter, a shoe support, and means for causing relative movement of translation of said cutter and shoe support along paths successively in two directions during the rotation of the cutter so that said cutter is caused to bevel the rear end of the sole of the shoe adjacent to the heel-seat and to trim simultaneously the opposite sides of the heel-seat.
14. In a heel-seat fitting machine, a rotary cutter, a shoe support, and means for causing relative movement of translation between said cutter and said shoe support successively in a plurality of directions during the rotation of the cutter to cause the cutter to bevel the rear end of the heel-seat, to trim the sides of the heel-seat to produce a substantially horseshoe shaped piece of waste, and to continue the cutting action to remove said piece of waste from the sole.
15. In a heel-seat fitting machine, a trimming cutter, a shoe support, means for causing relative movement of translation of said cutter and said shoe support to cause the cutter to remove surplus material from the heel-seat of the sole of a shoe carried thereby, and means for causing additional relative movement in a different direction to cause said cutter to make a cut forwardly and downwardly into the sole of the shoe adjacent to the heel breast line to form a flap
- beneath which the forward end of a Louis heel may be inserted.
16. In a heel-seat fitting machine, a rotary cutter, a shoe support, and means for causing relative movement of translation of said cutter and shoe support in a plurality of directions to cause the cutter to bevel both the rear end and sides of the heel-seat of the sole of a shoe carried by said support and to cut a flap in said sole to serve as a support for the projecting forward end of the breast of a Louis heel to be attached to said shoe.
17. In a heel-seat fitting machine, a rotatably mounted hollow cylindrical cutter, a shoe support, and means for causing relative movement of translation of said cutter and shoe support in a direction substantially parallel to the axis of the cutter to cause the cutter to trim away surplus material around the periphery of the heel-seat of a shoe mounted upon said support.
18. In a heel-seat fitting machine, a rotary trimming cutter having a circular cutting edge, a shoe support, and means for effecting relative movement of translation of said cutter and shoe support to bring the cutter into engagement with and cause it to remove surplus material from the heel-seat of the sole of a shoe adjacent to its rear end and for effecting additional movement to cause the same cutter to remove surplus material from the side of the heel-seat of said sole.
19. In a heel-seat fitting machine, a rotary trimming cutter, a shoe support, and means for effecting relative movement of translation of said cutter and shoe support to bring the knife into engagement with and cause it to remove surplus material from the heel-seat of the sole of a shoe adjacent to its rear end and for effecting additional movement to cause the same cutter to remove surplus material simultaneously from the sides of the heel-seat of said sole.
20. In a heel-seat fitting machine, a trimming cutter, a shoe support, means for slidably and pivotally supporting said shoe support arranged to allow movement of translation thereof with respect to the trimming cutter, and means for controlling said shoe support arranged automatically to cause it to bring the rear end of a sole into engagement with the trimming cutter to trim the rear of the heel-seat, to tilt the shoe, and to give it an additional movement of translation to cause the cutter to remove surplus material from the sides of the heel-seat of the sole.
21. A machine for trimming surplus material from shoes, said machine having a hollow rotating knife with a cutting edge at one end thereof, and means for introducing a shoe into the interior of the knife arranged to cause the shoe to engage the rotating cutting edge of the knife as the

shoe is introduced into the knife, whereby the knife cuts away stock from the shoe to form a convex surface upon the shoe.

22. A machine for trimming surplus material from shoes having a hollow substantially cylindrical rotating knife with a cutting edge at one end thereof, a shoe support, and means for causing relative movement of the shoe support and the rotating knife substantially in the direction of the axis of rotation of the knife to introduce a shoe carried by the support into the interior of the cylindrical knife arranged to cause mutual engagement of the shoe and the cutting edge of the knife, whereby surplus material is trimmed from the shoe and a convex surface is formed thereupon.

23. A machine for trimming surplus material from shoes having a hollow rotating knife with a cutting edge at one end thereof, and a last support arranged for movement in the general direction of the axis of rotation of the knife thereby to introduce a shoe upon a last carried by the support into the interior of the knife and to cause the shoe to engage the rotating cutting edge of the knife as the shoe is introduced into the knife, whereby the knife cuts away surplus stock and forms a convex surface upon the shoe.

24. A machine for trimming surplus material from shoes, said machine having a hollow substantially cylindrical rotating skiving knife having a sharp cutting edge at one end thereof, a work support, means for causing relative movement of the work support and the skiving knife in the general direction of the axis of rotation of the knife to introduce the shoe into the interior of the cylindrical knife to cause cutting engagement of the shoe and the knife and form a convex surface on said shoe, and means for causing relative movement of the rotating knife and the work about an axis at an angle 45 to the axis of rotation of the knife during the skiving action of the knife.

25. In a heel-seat fitting machine, a rotary cutter, a shoe support, means for causing relative movement of translation of said cutter and shoe support to cause the cutter to remove surplus material simultaneously along the sides of the heel-seat of the sole of a shoe, and means for imparting additional movement in another direction to cause the trimming cutter to complete the trimming cut at a bevel to the tread surface of the sole.

26. In a heel-seat fitting machine, a rotary cutter, a shoe support, means for causing relative movement of translation of said cutter and shoe support to cause the cutter to remove surplus material along the sides of the heel-seat of the sole of a shoe, and means for imparting additional movement in another direction to cause the trimming

cutter to complete the trimming cut at a bevel to the tread surface of the sole.

27. In a heel-seat fitting machine, a trimming cutter, a shoe support movably mounted to present the heel-seat of the sole of a shoe to said cutter to remove surplus material simultaneously along the opposite sides of the heel-seat, and means for imparting an additional movement to said shoe support in another direction to cause said cutter to make a cut at an angle to the tread surface of the sole.

28. In a heel-seat fitting machine, a trimming cutter, a movably mounted shoe support, a presser roll disposed adjacent to said cutter and arranged to bear against the sole of the shoe in advance of the cutter when a movement of translation is imparted to the shoe support to cause the cutter progressively to remove surplus material from the heel-seat of the sole of a shoe carried thereby, and means for moving said shoe support in a plurality of paths during the trimming operation to cause the trimming cutter to operate upon the heel-seat of the sole.

29. In a heel-seat fitting machine, a rotary cutter arranged to trim simultaneously the opposite sides of the heel-seat of a shoe, a movable support for said shoe, and self-adjusting crease-engaging fingers mounted adjacent to said cutter for movement toward and away from said shoe and arranged to engage the rand crease at the rear of said shoe and to follow around the sides of the heel-seat of the shoe progressively to distort the edges of the sole of the shoe as the latter is presented to the cutter.

30. In a heel-seat fitting machine, a rotary cylindrical cutting blade, a shoe support, means for engaging and distorting the edges of the heel-seat of the sole, and means for causing relative movement of translation between said blade and said shoe support to cause the blade to trim surplus material from the part of the sole which is distorted by said means.

31. In a heel-seat fitting machine, a shoe support, a trimming cutter, means for causing relative movement of said support and said cutter to cause the cutter to trim surplus material from the periphery of the heel-seat of the sole of a shoe, and means moving relatively to the shoe support during the trimming operation and acting progressively with the cutter at opposed points to lift the edges of the sole away from the upper prior to the action of the cutter.

32. In a heel-seat fitting machine, a rotary trimming cutter, a shoe support adapted to be tilted relatively to the cutter, means for causing relative movement between said support and said cutter to cause the cutter to remove surplus material from the heel-seat of the sole of a shoe, and narrow crease engaging fingers supported for movement to

ward and away from a shoe on said support arranged to engage the rand crease of the shoe at substantially opposed points during the relative movement of the cutter and shoe.

5 33. In a heel-seat fitting machine for boots and shoes, a hollow rotary cutter mounted so that the heel end of a shoe can be projected into the cutter to cause the cutter to bevel the heel-seat of the sole of a shoe to remove 10 surplus material therefrom, and means for engaging and distorting the edges of the heel-seat of the sole of a shoe presented to said cutter.

15 34. In a heel-seat fitting machine for boots and shoes, a hollow rotary cutter rotatably mounted so that the heel end of a shoe can be projected into the cutter to cause the cutter to bevel the heel-seat of the sole of a shoe to remove surplus material therefrom, 20 and means adapted to enter the rand crease of said shoe constructed and arranged to act progressively to lift the edge of the sole away from the upper prior to the action of the cutter as the shoe is presented thereto.

25 35. In a heel-seat fitting machine, a rand crease engaging finger having its end beveled and tapered whereby said finger may be brought into the rand crease of a shoe, and means for causing relative movement of the shoe and said finger lengthwise of the shoe to cause the finger progressively to distort the edge of the sole around the curved end of the heel-seat of the sole of the shoe.

30 36. In a heel-seat fitting machine, a shoe support, a trimming cutter arranged to trim the opposite sides of the heel-seat of a shoe on said support, rand crease engaging fingers supported adjacent to the cutter for movement toward and away from said shoe support in a plane transverse to the length of the shoe, and means to cause relative movement of the fingers and cutter and of the support in the direction of the length of the shoe as the shoe is presented to the cutter, said fingers being constructed and arranged progressively to distort the edge of the sole for the action of the trimming cutter.

35 37. In a heel-seat fitting machine, a trimming cutter, rand crease engaging fingers supported for movement toward and away from one another adjacent to said cutter, said fingers being beveled in two directions so that they will engage the rand crease at the rear of a shoe presented to said cutter and follow around the heel-seat, and means for causing relative movement of the shoe and said fingers lengthwise of the shoe progressively to distort the edge of the sole as the shoe is presented to the cutter.

40 38. In a heel-seat fitting machine, a trimming cutter, a shoe support, rand crease engaging fingers supported beside the cutter for movement toward and away from said shoe support in a plane transverse of the

length of a shoe carried on said support, and means to cause relative movement of the fingers and cutter and of the support in the direction of the length of the shoe as the shoe is presented to the cutter, said fingers being constructed and arranged to engage the rand crease of the shoe at the rear end thereof and to follow around the heel-seat progressively to distort the edge of the sole for the action of the trimming cutter. 70

39. In a heel-seat fitting machine, fingers having beveled ends adapted to enter the rand crease between the sole and the upper of a shoe with rand crease entering edges inclined relatively to the length of the shoe, 80 means for supporting said fingers for adjustment around their axes and for movement toward and away from said shoe, means for causing relative movement of the fingers and the shoe in the direction of the length of the shoe and means for resiliently urging said fingers into engagement with the rand crease of said shoe. 85

40. In a heel-seat fitting machine, a shoe support adapted to be tilted, rand crease engaging fingers supported for pivotal movement about a longitudinal axis substantially parallel to the length of the sole of the shoe carried by said support and about axes transverse to the length of said shoe sole, 95 and means for resiliently urging said fingers into engagement with the rand crease of said shoe. 90

41. In a heel-seat fitting machine, a shoe support adapted to be tilted, and rand crease 100 engaging fingers having reduced ends adapted to be inserted in the rand crease of a shoe mounted upon said support, said fingers being pivotally mounted about axes extending transversely of the length of the 105 shoe carried by said support.

42. In a heel-seat fitting machine, a shoe support adapted to be tilted, rand crease engaging fingers having reduced ends adapted to be inserted in the rand crease of a shoe mounted upon said support, said fingers being pivotally mounted about axes extending transversely of the length of the shoe carried by said support, and means for resiliently maintaining the reduced ends of said fingers in a predetermined plane. 110

43. In a heel-seat fitting machine, a shoe support, a trimming cutter, means for causing relative movement between said support and said cutter to cause the cutter to remove surplus material from the heel-seat of the sole of a shoe, and crease-engaging fingers movably mounted adjacent to said cutter and arranged to engage the rand crease of the shoe at opposed points during 115 the relative movement of the cutter and the shoe, said fingers being self-adjusting about an axis transverse to the length of the shoe. 120

44. In a heel-seat fitting machine, a trimming cutter, a slidable support, a shoe sup- 125

port pivotally mounted upon said slidable support, and means for imparting a movement of translation to said slidable support and for automatically tilting said shoe support upon the slidable support constructed and arranged to cause the trimming cutter to remove surplus material from the end and sides of the heel-seat of the sole of a shoe carried thereby.

10 45. In a heel-seat fitting machine, a trimming cutter, a movably mounted shoe carrier, means for imparting movement of translation to said carrier to bring the shoe into engagement with the cutter, and means for automatically changing the position of the shoe upon the carrier constructed and arranged to cause the trimming cutter to remove surplus material from the end and sides of the heel-seat of the sole of a shoe.

20 46. In a heel-seat fitting machine, a rotary trimming cutter, a movably mounted shoe support, and a presser roll disposed adjacent to the cutting edge of said cutter and arranged to bear against the sole of the 25 shoe in advance of the cutter when a movement of translation is imparted to the shoe support to cause the cutter progressively to remove surplus material from the heel-seat of the sole of a shoe carried thereby.

30 47. In a heel-seat fitting machine, a trimming cutter, a movably mounted shoe carrier, a presser roll disposed adjacent to said cutter and arranged to bear against the sole of the shoe in advance of the cutter when 35 a movement of translation is imparted to the shoe carrier to cause the cutter progressively to remove surplus material from the sides of the heel-seat of the sole of a shoe carried thereby, and means for tilting said 40 shoe upon said carrier to cause the cutter also to act upon another part of the heel-seat of the sole of a shoe.

48. In a heel-seat fitting machine, a trimming cutter, a pivotally mounted runway, 45 a shoe support slidably carried by said runway constructed and arranged so that movement of translation of said shoe support with respect to the trimming cutter may be imparted to cause the trimming cutter to remove surplus material from the heel-seat 50 of the sole of a shoe carried thereby, and means for tilting said runway to vary the action of said trimming cutter.

49. In a heel-seat fitting machine, a trimming cutter, a pivoted runway, a shoe support slidably mounted upon said runway, operator controlled means for imparting a movement of translation to said shoe support to cause said cutter to remove surplus 55 material from the heel-seat of the sole of a shoe carried thereby, and an operator controlled device constructed and arranged to tilt said runway to change the path of movement of the shoe support with respect to the trimming cutter to cause the latter

to make a cut at an angle to the tread surface of the sole of the shoe.

50. In a heel-seat fitting machine, a trimming cutter, a pivoted runway, a shoe support slidably mounted upon said runway, operator controlled means for imparting a movement of translation to said shoe support to cause said cutter to remove surplus material from the heel-seat of the sole of a shoe carried thereby, and an operator controlled device constructed and arranged to tilt said runway to change the path of movement of the shoe support with respect to the trimming cutter to cause it to make a cut at an angle to the tread surface of the sole of the shoe, said operator controlled means being constructed and arranged to be adjustably connected to the tilting means so that the angle of the resulting cut may be reversed.

51. In a heel-seat fitting machine, a trimming knife, a pivoted runway, a shoe support slidably mounted upon said runway, operator controlled means for sliding the shoe support upon the runway to bring a shoe mounted upon said support into engagement with the knife, adjustable stops, and an operator controlled device constructed and arranged to tilt the runway in either direction to an extent determined by said stops to change the path of movement of the shoe support with respect to the trimming knife and cause said knife to make cuts at different angles to the tread surface of the sole of the shoe.

52. In a heel-seat fitting machine, a trimming cutter, a runway, a slidable support on said runway, a shoe support pivotally mounted upon said slidable support, an actuating slide, a latch between said actuating slide and said slidable support, and a tilting lever connecting said actuating slide and said shoe support all constructed and arranged so that movement imparted to the actuating slide will cause a combined movement of translation and tilting movement of the shoe support to bring the shoe into engagement with the trimming cutter to remove surplus material from the heel-seat of the sole of a shoe.

53. In a heel-seat fitting machine, a trimming knife, a runway, a slidable support on said runway, a shoe support adjustably carried by said slidable support, an actuating slide positioned adjacent to said slidable support, a latch arranged to connect the actuating slide and the slidable support for movement as a unit, means controlled by the position of the slidable support in the runway determining the effectiveness of said latch in interconnecting said slides, and means for connecting said actuating slide to said shoe support independently of the slidable support whereby a movement of translation may be imparted to the slidable

support with the shoe support occupying different positions relatively thereto.

54. In a heel-seat fitting machine, a trimming knife, a runway, a slidable support on said runway, a shoe support pivotally mounted upon said slidable support, an actuating slide, latches arranged to interconnect said actuating slide and said slid-
10 able support in a plurality of positions, a tilting lever connecting said actuating slide and said shoe support, and means upon said runway controlling said latches whereby said shoe support may be given a movement of translation, a tilting movement and an additional movement of translation to cause the knife to trim surplus material from the heel-seat of a shoe carried by the support.

55. In a heel-seat fitting machine, a ring-knife, a shoe support, said support and said ring-knife being relatively movable to cause movements of translation between a shoe on said support and the ring-knife so that the ring-knife is caused to remove surplus material along the periphery of the heel-seat of the sole of the shoe, and a cutter constructed and arranged for movement transversely of the sole of the shoe at approximately the heel breast line.

56. In a heel-seat fitting machine, a rotatably mounted trimming cutter arranged to remove surplus material from the heel-seat of the sole of a shoe, and a breast cutting knife pivotally mounted for rotation about an axis coinciding with the axis of the trimming cutter arranged to make a transverse cut adjacent to the heel breast line.

57. In a heel-seat fitting machine, a knife blade positioned in a plane angularly related to the plane of the bottom of the sole of a shoe and movable transversely of the shoe sole in a curved path to cut the shoe sole and form shoulders therein adjacent to the heel breast line for co-operation with a heel to be attached to the shoe.

58. That improvement in methods of trimming surplus material from the heel-seats of the soles of shoes which comprises introducing the rear end of a shoe to be trimmed into the interior of a hollow rotating knife having a cutting edge at one end thereof by relative movement of the shoe and the knife in the general direction of the axis of rotation of the knife to effect mutual engagement of the heel-seat of the sole and the cutting edge of the knife, and continuing relative movement of the knife and shoe to remove surplus material simultaneously from the opposite sides of the heel-seat during said relative movement.

59. That improvement in methods of trimming surplus material from the heel-seats of the soles of shoes which comprises introducing the rear end of a shoe to be

trimmed into the interior of a hollow substantially cylindrical rotating knife having a cutting edge at one end thereof by relative movement of the shoe and the knife in the general direction of the axis of rotation of the knife to effect mutual engagement of the heel-seat of the sole and the cutting edge of the knife, and causing successive relative movements in a plurality of angularly related directions to remove material first from the rear end of the heel-seat and then from a side thereof.

60. That improvement in methods of trimming surplus material from the heel-seats of the soles of shoes which comprises introducing the rear end of a shoe to be trimmed into the interior of a hollow substantially cylindrical rotating knife having a cutting edge at one end thereof by relative movement of the shoe and the knife in the general direction of the axis of rotation of the knife to effect mutual engagement of the heel-seat of the sole and the cutting edge of the knife, and continuing relative movement of the knife and shoe in a direction first to cause the knife to bevel the rear end of the heel-seat and then in a direction to cause the knife to trim material from the opposite sides thereof and then in a direction to cause the knife to emerge from the tread surface of the sole.

61. That improvement in methods of trimming surplus material from the heel-seats of the soles of shoes which comprises introducing the rear end of a shoe to be trimmed into the interior of a hollow substantially cylindrical rotating knife having a cutting edge at one end thereof by relative movement of the shoe and the knife in the general direction of the axis of rotation of the knife to effect mutual engagement of the heel-seat of the sole and the cutting edge of the knife, continuing relative movement of the knife and shoe to remove a horseshoe shaped piece of material from the heel-seat, and causing subsequent movement in a different direction to produce a cut directed inwardly away from the tread surface of the heel to make a short thick flap adjacent to the heel breast line.

62. That improvement in methods of trimming surplus material from a work piece of shoe stock, attached to a shoe which comprises separating portions of the work piece from the shoe, introducing the major portion of said work piece to be trimmed into the interior of a hollow rotating knife having a cutting edge at one end thereof and causing the work piece while it is within the knife to engage the rotating cutting edge of the knife so that the knife trims a small projecting portion from the work piece and forms a convexly curved surface upon the work piece.

63. That improvement in methods of

- trimming surplus material from a work piece of shoe stock attached to a shoe characterized by the separation of portions of the work piece from the shoe, and the introduction of a major portion of said work piece to be trimmed into the interior of a hollow rotating skiving knife having a cutting edge at one end thereof in such a manner that the work piece as it is introduced 5 within the knife engages the rotating cutting edge of the knife so that the knife skives surplus material from the work piece and forms a convexly curved surface upon the work piece.
- 15 64. That improvement in methods of trimming surplus material from a work piece of shoe stock attached to a shoe which comprises separating portions of the work piece from the shoe, introducing a major 20 portion of said work piece to be trimmed into the interior of a hollow substantially cylindrical rotating knife having a cutting edge at one end thereof by relative movement of the work piece and the knife in the 25 general direction of the axis of rotation of the knife, and causing mutual engagement of the work piece and the cutting edge of the rotating knife so that the knife during 30 said mutual engagement trims a small projecting portion from the work piece and forms a convexly curved surface upon the work piece.
65. That improvement in methods of trimming surplus material from a work piece 35 of shoe stock attached to a shoe which comprises separating portions of the work piece from the shoe, introducing said work piece to be trimmed into the interior of a substantially cylindrical rotating skiving knife having 40 a cutting edge at one end thereof by relative substantially rectilinear movement of the work piece and the knife in the general direction of the axis of rotation of the knife, thereby, causing mutual engagement 45 of the work piece and the cutting edge of the rotating knife to cause the knife to skive a convexly curved surface on the work piece and causing relative movement of the rotating knife and the work piece in a direction 50 at an angle to the direction of the axis of rotation of the knife while the knife is in cutting engagement with the work piece to cause the knife further to operate on the work piece.
- 55 66. That the improvement in methods of trimming surplus material from the heel-seats of shoes which consists in progressively moving a member underneath the rear portion of a sole attached to a shoe relatively 60 to the shoe and in the general direction of the length thereof to distort the periphery of the heel-seat of the sole of a shoe as relative movement of translation is produced between a cutter and said sole to push the cutter through the sole so as to trim away 65

the surplus material thus distorted out of its normal position.

67. That improvement in methods of trimming surplus material from the heel-seats of the soles of shoes which consists in 70 moving a work distorting device underneath the rear portion of a sole attached to a shoe relatively to the shoe as relative movement of translation is produced between a cutter and said sole to cause the distortion first of 75 the rear end of the heel-seat of the sole and its reduction by said cutter and the subsequent progressive distortion of the sides of the heel-seat and the removal of the material thus distorted by said cutter to produce a beveled surface within the periphery of the sole of the shoe suitable for engagement with the heel attaching surface of a heel to be applied to the shoe.

68. That improvement in methods of 80 trimming surplus material from the heel-seats of shoes which comprises producing relative movement of translation of a cutter and a shoe first in a direction to bevel the rear of the heel-seat and then in a direction 85 angularly related thereto to trim away surplus material simultaneously from the opposite sides of the heel-seat, thereby producing a horseshoe shaped piece of surplus material for removal prior to the attachment of 90 a heel to the shoe.

69. That improvement in methods of trimming surplus material from the heel-seats of shoes which consists in producing 95 relative movement of translation of a cutter and a shoe along a plurality of angularly related directions to cause the beveling of the rear end of the heel-seat by movement in one direction and the beveling of the sides of the heel-seat by movement in another 100 direction thereby to form a horseshoe shaped chip of surplus material and removing said chip by relative movement of said cutter and the shoe in still another direction.

70. A heel-seat fitting machine having, in combination, a support for a shoe, a cutter mounted for progressive movement transversely across the sole of the shoe from one edge of the sole to the other substantially at its breast line whereby the cutter operates first on one side and later on the other side of the heel-breast line of the sole to form a heel-breast-receiving abutment in the sole, and means for moving the cutter heightwise of the shoe to vary the depth at 115 which the cutter operates on the sole of the shoe.

71. A heel-seat fitting machine having, in combination, a support for a shoe, a cutter mounted for progressive movement transversely across the sole of the shoe carried by the support from one edge of the sole to the other substantially at its heel-breast line whereby the cutter operates first at one end 120 and later at the other end of the heel-breast 125

line of the sole to form a heel-breast-receiving abutment in the sole, and means for moving the cutter heightwise of the shoe during said transverse movement to cause the cutter to run out of the sole before the 5 median line is reached and then after the median line has been passed to enter the sole whereby the heel-breast-receiving abutment formed in the sole by the cutter will consist of two separate portions which terminate 10 at opposite edges of the sole of the shoe.

72. A heel-seat fitting machine having, in combination, a support for a shoe, a cutter mounted for progressive movement transversely across the sole of a shoe carried by 15 the support, from one edge of the sole to the other, substantially at its heel-breast line, whereby the cutter operates first at one end and later at the other end of the heel-breast 20 line of the sole to form a heel-breast-receiving abutment in the sole, and means for moving the cutter heightwise of the shoe as it operates upon the sole to control the depth to which the knife cuts as it passes across 25 the sole.

73. A heel-seat fitting machine having, in combination, a support for a shoe, a cutter, and means constructed and arranged to move the cutter progressively in a path extending 30 transversely across the sole of a shoe upon the support from one edge of the sole to the other whereby the cutter operates first at one end and later at the other end of the heel-breast line of the sole and also to move the 35 cutter heightwise of the shoe to vary the depth to which the cutter operates upon the sole of the shoe as it moves in said path transversely of the sole.

74. A heel-seat fitting machine having, in combination, means constructed and arranged to enter the rand crease of a shoe, a member arranged to engage the bottom of the sole of the shoe and to cooperate with 40 said means for positioning the shoe in the machine, a cutter having a blade curved about an axis extending lengthwise of the positioned shoe and terminating in a correspondingly curved cutting edge, and means for causing relative movement of the cutter 45 and the shoe to trim the rear portion of the sole of the shoe to a shape suitable for receiving a heel.

75. A heel-seat fitting machine having, in combination, means constructed and arranged to engage the rear portion of the attaching face of a sole attached to a shoe, a member constructed and arranged to engage the tread face of the sole of the shoe and to 50 cooperate with said means for positioning and distorting the sole of the shoe in the machine, a knife having a blade curved about an axis extending lengthwise of the positioned shoe and terminating in a correspondingly curved cutting edge, and means for causing relative movement of the 55

knife and the shoe to trim the rear portion of the sole of the shoe for receiving the attaching face of a heel which is to be attached to the shoe.

76. A heel-seat fitting machine having, in combination, means constructed and arranged to enter the rand crease of a shoe, a member constructed and arranged to engage the bottom of the sole of the shoe and to cooperate with said means for positioning the shoe in the machine, a knife having a concave portion terminating in a cutting edge curved about an axis extending lengthwise of the shoe positioned in the machine, and means for causing relative movement of the knife and the shoe to trim the lateral marginal portions of the rear part of the shoe as the central portion of the rear part of the shoe lies within said concave portion. 70 75

77. A heel-seat fitting machine having, in combination, means constructed and arranged to enter the rand crease of a shoe, a member arranged to engage the bottom of the sole of the shoe to cooperate with said means for positioning the shoe in the machine, a cutter having a blade curved about an axis extending lengthwise of the positioned shoe and terminating in a correspondingly curved cutting edge, means for causing relative movement of the cutter and the shoe to trim the lateral rear portions of the sole of the shoe, and cutting means movable laterally of the positioned sole to form heel-breast-receiving shoulders upon 80 85 90 95 the sole. 100

78. A heel-seat fitting machine having, in combination, means constructed and arranged to engage the rear portion of the attaching face of a sole attached to a shoe, a member arranged to engage the tread face of the sole of the shoe and to cooperate with said means for positioning and distorting the sole of the shoe in the machine, a knife having a blade curved about an axis extending lengthwise of the positioned shoe and terminating in a correspondingly curved cutting edge, means for causing relative movement of the knife and the shoe to trim the marginal rear portions of the sole of the shoe by cuts extending lengthwise of the sole thereby forming a horseshoe-shaped piece of surplus material which is attached to the sole in the vicinity of its breast line, and a knife mounted for movement at an angle to said axis for severing the horseshoe-shaped piece of material from the sole and for forming heel-breast-receiving shoulders upon the sole. 105 110 115

79. A heel-seat fitting machine having, in combination, means for positioning a shoe, and a cutter mounted for progressive movement transversely across the sole of the shoe from one edge of the sole to the other substantially at its heel-breast line in a curved path whereby the cutter operates first at 120 125 130

one end and later at the other end of the heel breast line of the sole to form a heel-breast receiving abutment in the sole.

80. A heel-seat fitting machine having, in combination, a support for a shoe, a cutter, and means for progressively moving the cutter in a curved path transversely across the sole of the shoe mounted upon the support from one edge of the sole to the other whereby the cutter operates first at one end and later at the other end of the heel breast line of the sole, said means also being constructed and arranged to cause the cutter to have a component of movement heightwise of the shoe as it moves transversely of the shoe to vary the depth to which the cutter operates on the sole of the shoe during its movement transversely across the sole.

81. A heel-seat fitting machine having, in combination, a support for a shoe, a knife, and means for progressively moving the knife in a curved path transversely across the sole of the shoe mounted upon the support from one end of the sole to the other whereby the knife operates first at one end and later at the other end of the heel breast line of the sole, said means also being constructed and arranged to cause the knife to have a component of movement heightwise of the shoe as it moves transversely of the shoe to vary the depth to which the knife operates on the sole of the shoe during its movement transversely across the sole.

In testimony whereof I have signed my name to this specification.

SIDNEY J. FINN.
